UNITED STATES PATENT OFFICE.

TEODORO LARREY AND LUIS GODARD, OF MEXICO CITY, MEXICO.

STEAM-SUPERHEATING SYSTEM FOR STEAM ENGINES.

Application filed December 7, 1925, Serial No. 73,921, and in Mexico November 19, 1925.

This invention relates to superheaters and heat distributing deflectors for locomotives, being a modification of the construction shown in our prior Patent No. 1,563,503, granted December 1, 1925, and application No. 720,618.

The main object is to make the construction of the superheating units more simple and to facilitate the repair of the fire tubes. 10 Our apparatus is adaptable to old locomotives using fire tubes of one or several diameters.

Another object is to provide a throttle valve for superheated steam which is counterbalanced by saturated steam; the throttle valve chest, however, does not form a receptacle or dome for such steam.

This construction adapts itself as well to existing locomotives in which the exhaust 20 pipe is rather near the tube sheet.

Owing to this construction it is possible to superheat the steam stepwise thereby obtaining a very high final temperature; the saturated steam passing simultaneously 25 from one chamber through a number of superheating tubes towards another chamber, whereby it reaches a higher temperature.

From the second chamber the steam is 30 led through other superheating tubes to a third chamber thus increasing its temperature, and may be led through still other superheating tubes to subsequent chambers, according to the increase of temperature required.

The superheated steam passes through a 35 throttle valve in the smoke box on its way to the steam chest, and steam from one of the chambers is led to the heaters, blowers, etc.

We obtain the above and other objects by the constructions shown in the accompanying drawings, in which:

Fig. 1 is an elevation of a locomotive 40 smoke box, with our deflecting superheater.

Fig. 2 is a side elevation thereof.

Fig. 3 is a longitudinal cross section of 45 two superheating tube units of different diameters.

Fig. 4 is a vertical cross section of the deflecting chambers.

Fig. 5 is a side elevation of a modified construction of our superheater.

Fig. 6 is an end elevation of a locomotive, provided with the modified construction shown in Fig. 5.

Fig. 7 is a vertical longitudinal cross section of a fraction of a four-chamber deflector.

Fig. 8 is a diagram showing superheating units of three groups, which connect pairs of chambers in a linked manner.

Referring to Figs. 1, 2, 3 and 4 of the drawings, (1) is the smoke box, (2) the boiler wall, (3) the tube sheet, (4) the medium sized fire tubes, (5) the large fire tubes and (6) the small fire tubes or flues.

Two dry pipes (7) pierce the tube sheet (3), each connected by an elbow (8) with the upper part of the outer or front chamber (9) of the deflecting superheater, which by means of superheating tube units (38) communicates with the middle chamber (10) and this by the tube units (29) with the inner or rear chamber (11), which discharges superheated steam by the connection (12) and passes it through the throttle valve, from where it goes by the tubes (14) directly to the steam chests.

The casing or box (13) of the throttle 80 valve is mounted upon the boiler wall (2), and upon the valve seat (15) the valve proper (16) rests when closed. Packings (17) are provided on the valve (16) which receives sliding movement up and down by 85 the valve stem (18) inserted through the cover (19), and by further bar connections from the cab.

From one of the elbow pipes (8), connected to the dry pipes (7), leads a small 90 tube (20) which feeds saturated steam to the back pressure chamber (21) of the throttle valve, in order to counterbalance the valve and make its operation easier.

The deflector shown in Figures 3 and 4 95 has three parallel chambers, though more chambers may be adopted; and an auxiliary, cast iron deflecting member (22) is supported by legs (23) against the lower edge of the deflector.

From the top of the rear chamber (11) a tube (24) extends, feeding all the auxiliary apparatus such as heaters, blower etc. The deflector comprises four plates (25), (26), (27) and (28), all of which are pierced by 100 the slightly conical ends of the superheating tubes (29), which are provided at opposite ends with stoppers (30) and (31); each last-named stopper having fastened to it a flat bar (32) that is held within the tube (29) but terminates short of the stopper (30).

The portion of the tube (29) that passes through the deflector is provided with an exterior shoulder (33) which rests against the plate (25), this portion being also provided with the perforation (34) for discharging and the perforation (35) for admitting steam; the tube (29) being fastened by the nut (36) which is tightened against the copper packing disk (37).

10 The superheating tubes of larger diameter are like the tubes (29), each having a ring (39) soldered to its exterior, which ring rests against the plate (25) when the nut (40) is tightened; the tube (38) being provided with an inlet aperture (41) for admitting saturated steam from the chamber (9) and also an aperture (42) for discharging steam into the middle chamber (10).

Between the plates (25), (26), (27), (28) are seen the spacers (43), which are screwed into the plate (27); other spacers (44) are screwed into the plate (26) so that their reduced extensions (45) abut against each other at the central line of the chamber (10).

25 Stay bolts (46) pass through the four plates (25), (26), (27), (28) so as to maintain the plates tightened against the spacers (43) and (44), thus making the drilling through the plates much easier. Into the 30 drilled holes the superheating units are inserted and tightened, the plate (26) is soldered to the plate (25), and the plate (27) is soldered to the plate (28). Lastly the two halves of the heat deflector are 35 soldered together along the middle line (47) which is exactly where the two plates (25) and (28) are joined together.

The saturated steam passes by the dry pipe (7) to the front or outer chamber (9), 40 and then through the perforations (41) into the large superheating pipes (38), where it passes as seen in Fig. 3 below the flat bar (32) and escapes by the discharge opening (42) into the middle chamber (10) and by 45 that time it has been converted into superheated steam. Thereupon it passes through the perforations (35) into the superheating tubes (29), traveling first below and then above the flat bars (32) and escaping by the 50 openings (34) into the chamber (11). From there, it passes through the connection (12) to the casing (13) of the throttle valve when the latter is opened, and thence by the pipes (14) to the steam chests, some steam also 55 being supplied from chamber (11) to the auxiliary apparatus by the small pipe (24).

We have described the course followed by the steam in the example shown although it 60 may be reversed, that is, the steam may enter from the chamber (11) as saturated steam and flow out from the chamber (9) as superheated steam; or it may enter by the middle chamber (10) as saturated steam and flow out from either chamber (10) or (11) 65 as superheated steam.

With the object of facilitating the rapid flow of the saturated steam, it may be advisable to use tubes (38) of larger diameter but of course in less number so as to correspond in capacity with the total capacity 70 of those tubes which receive the steam from the chamber (9), then passing the steam through other tubes and chambers with the object of superheating it still more, and at last discharge it through the throttle valve, 75 as already explained. According to another possible arrangement, all the superheating units may be of the same diameter, compensating of course by the number of units between the chambers for the difference in the volume of steam, as a consequence 80 of the expansion produced by the increasing temperature.

Each superheating tube or unit should have the same interior diameter throughout, 85 and only the extreme end from the shoulder (33) is reduced, in order to make that extension of the tube slightly conical. This can be done by previously inserting a mandrel up to the shoulder (33) so as to be able 90 to roll out the exterior of said tube extension, leaving it thicker near the shoulder and of the same thickness at the end as the rest of its length. The stoppers (30) and (31) are applied by fire welding and the stopper (30) has an annular recess so as to attach it 95 still better to the tube, while the flat bar is also secured while hot to the stopper (31).

It is advisable to make the tubes (38) of 100 larger diameter somewhat longer than the others, so that they may penetrate for a greater distance into the fire tubes than the superheating tubes (29).

Figures 5 and 6 show a modification which 105 renders the superheater applicable to the locomotives already in use, some of which have an exhaust pipe located very near the fire tubes, so that there would be no room for a throttle valve between the chimney and tube sheet. Here the flue sheet (3) is shown with the fire tubes (6), all of which are of 110 one and the same diameter, into which are inserted the superheating units (29) that project through the three chambers (9), (10) and (11) of the heat deflector. The chamber (9) is connected to the dry pipe (72), from which extends the small tube (20) which carries saturated steam to the back pressure chamber (21) of the throttle valve casing (13), in order to balance the 115 valve, as was already explained. Here the superheated steam is discharged from the chamber (11) by the two branch pipes (73), which are joined to casing (13), from which the superheated steam is discharged by the 120 two pipes (14) to the steam chests. 125

In Fig. 7 is shown a modification comprising four chambers, formed by the plates (48), (49), (50), (51), (52).

Here the spacing bolts (43) and (44) 130

abut with their extreme points against the middle plate (50). The tubes (53) are provided with stoppers (30) at one end, and with stoppers (54) at the other end, each stopper (54) having an annular groove (55) into which a part of the tube (53) is pressed while hot, the groove thus formed in the tube being afterwards filled with soldering material (56) so as to fasten the stopper (54) within the said tube (53). The flat bar (32) is inserted into the tube and fastened by a rivet (57), while at the end of said stopper and tube is fastened a bushing (58) the end of which extends inward towards the center and through which projects the threaded reduced end (59) of the stopper. On this is fastened the nut (60), and the opposite end of the bushing carries an outwardly-extending shoulder (61) the bushing being also soldered at (62) to the tube (53). A copper gasket (63) is inserted between the shoulder (61) and the plate (48) of the deflecting device, and a copper gasket (64) between the plate (52) and the nut (60). The plate (51) is soldered to the plate (52) at (65), said plate (52) being folded over at the bottom and soldered at (66) to the plate (48) as well as to the middle plate (50), while the plate (49) is soldered to the plate (48) at (67). In a similar manner to that shown in Fig. 4, saturated steam enters into the chamber (68), passes therefrom into the superheating tubes of greater length, then enters into the chamber (69) which feeds the tubes of medium length, then enters into the chamber (70) which feeds steam to the tubes shown as of the shortest length, and these will finally feed superheated steam of the highest temperature to the chamber (71) which supplies it by way of the throttle valve to the valve chests.

Though not shown in the drawing, a safety valve may be connected to the small tube (24) which feeds steam to the auxiliary apparatus such as the heaters and blowers, etc.

What we claim is:—

1. A steam superheating system for steam engines, comprising a deflector having its interior partitioned to form a plurality of substantially-counterpart chambers disposed one in front of another, one of which is connected with a saturated steam supply; piping leading from a second chamber of the deflector for supplying superheated steam to the engine cylinders; a throttle valve in said piping for controlling the passage of the steam therethrough; and a multiplicity of tubular superheating units arranged in a plurality of distinct groups and mounted at one end in the deflector and projecting through the several chambers thereof, each unit being partitioned interiorly to form oppositely-extend-

ing, longitudinal inlet and outlet compartments which communicate with each other solely at the end remote from the deflector; the inlet compartments of all the tubes in one group of units having inlet ports which open directly into the first chamber of the deflector to receive saturated steam therefrom, and the outlet compartments of all the tubes of such group having outlet ports which open directly into a third chamber to discharge the then superheated steam thereinto; while the inlet compartments of all the tubes of a second group of units have inlet ports which open directly into said third chamber to receive the superheated steam therein, and the outlet compartments of all the tubes of said second group having outlet ports opening directly into the second-named chamber to discharge the superheated steam into that chamber.

2. A steam superheating system, according to claim 1, in which the throttle valve has a back-pressure feed connection with the saturated steam supply.

3. A steam superheating system, according to claim 1, in which the partitions within the deflector extend vertically from top to bottom thereof, the saturated steam supply connection of the first chamber of the deflector and the superheated steam outlet from the second-named chamber being located at the tops thereof.

4. A steam superheating system for steam engines, comprising a deflector having its interior partitioned to form a plurality of chambers, one of which is connected with a saturated steam supply, piping leading from another chamber of the deflector for supplying superheated steam to the engine cylinders, a throttle valve in said piping for controlling the passage of the steam therethrough, and a multiplicity of superheating tubes mounted at one end in the deflector and extending through the several chambers thereof and being partitioned interiorly to form oppositely-extending, longitudinal inlet and outlet compartments which communicate with each other solely at the end remote from the deflector to effect step-by-step heating of the steam; the end of each superheating tube mounted in the deflector having fitted thereon an externally-tapered sleeve, one end of which is turned inward toward the center and the other end of which is turned outward, and a stopper fitted in the tube at the first-named end thereof and on which said tube end is shrunk, said stopper projecting outward through the inwardly-turned end of the sleeve.

In testimony whereof we have affixed our signatures.

TEODORO LARREY.
LUIS GODARD.
